UNITED STATES PATENT OFFICE

WILLIAM F. THIEDE, OF WESTFIELD, NEW JERSEY, ASSIGNOR TO STANDARD OIL DEVELOPMENT COMPANY, A CORPORATION OF DELAWARE

APPARATUS FOR EXTINGUISHING FIRES IN TANKS

Application filed April 25, 1929. Serial No. 358,131.

This invention relates to improvements in equipment for distributing fire extinguishing material over the surface of inflammable liquids in tanks or the like. A particular object of my improvements is to provide efficient equipment of this character which shall not be readily injured in case the roof of the tank is blown off or the upper walls distorted. The invention will be fully understood from the following description read in connection with the accompanying drawings; in which

Fig. 1 is a section through an oil storage tank showing the improved equipment therein;

Fig. 2 is a transverse section on line II-II, Fig. 1;

Fig. 3 is a view similar to Fig. 1, but showing a modified type of equipment; and

Fig. 4 is a transverse section on line III-III.

Referring to Figs. 1 and 2, 1 denotes an oil storage tank and 2 a closed standpipe having a closed upper end above the normal level of liquid in the tank. The standpipe is mounted at some suitable location within the tank, preferably near the center. The standpipe receives a fire extinguishing material, especially foam, through a line 3, which enters the tank and standpipe below the normal level of liquid in the tank and is extended upwardly through the standpipe 2 and opens above the normal level of liquid in the tank. This line may be connected to the refinery foam supply, or it may receive foam forming chemicals through branches 4 and 5. In this case the line 3 serves as a mixing column for foam formation. Valves 6 and 7 are provided in lines 4 and 5, respectively.

Pairs of outlet pipes 8 are arranged at intervals throughout the length of the standpipe. These pipes are open at their ends for free discharge of foam upon the surface of oil in the tank.

Standpipe 2 may be supported by guy rods 9 or in any other suitable way which does not involve a connection to the roof or upper walls of the tank.

In the form of the invention shown in Fig.

3, the construction of the standpipe and supply line is substantially the same but the standpipe is mounted near the side of the tank and is secured thereto by straps 10 or other fastening means. The highest connection to the wall of the tank should not be much more than two-thirds of the distance from bottom to top of the tank. Pipes 8' extend outwardly from the standpipe. In large tanks it is desirable to provide a plurality of standpipes. Two of these are illustrated in Fig. 3, but it will be understood that any suitable number may be used.

In operating the equipment described, the valves in branches 4 and 5 are opened as soon as a fire is detected in the tank. Foam is formed in line 3 and overflows into the standpipe. The foam will flow through such of the outlets as are above the surface of oil in the tank. Owing to the arrangement of the outlets at various heights, the foam will in no case have to fall a substantial distance through a zone of heat before spreading over the surface of the oil. Moreover, in the improved equipment connections with the roof and upper walls of the tank have been avoided. In previous installations it has often happened that explosions in the tank have wrecked the foam supplying equipment before it has a chance to discharge any foam upon the burning oil. In the construction described herein, the standpipe will ordinarily remain in position even though the roof of the tank may be blown off and the upper walls crushed.

The foregoing description is merely illustrative and various changes may be made within the scope of the appended claims, in which it is my intention to claim all novelty inherent in the invention as broadly as the prior art permits.

I claim:

1. In fire prevention apparatus, a standpipe adapted to be disposed in a tank for inflammable liquid with its upper end above the normal level of the liquid, and a conduit of relatively small diameter entering the standpipe in close proximity to the lower end thereof and opening into the upper portion of the standpipe above the normal level of liq-

uid, the standpipe being provided with a plurality of longitudinally spaced outlets.

2. A storage device, comprising a tank adapted to contain inflammable liquid, a standpipe in the tank and having a closed upper end above the normal level of liquid in the tank, and a conduit of relatively small diameter entering the standpipe in close proximity to the lower end thereof and opening into the standpipe above the normal level of liquid, the standpipe being provided with a plurality of longitudinally spaced outlets.

3. A storage device, comprising a tank adapted to contain inflammable liquid, a standpipe in the tank and having an upper end above the normal level of liquid in the tank, and a conduit of relatively small diameter entering the tank and standpipe in close proximity to the lower end thereof and opening into the standpipe above the normal level of liquid, the standpipe being provided with a plurality of longitudinally spaced outlets.

WILLIAM F. THIEDE.
